Patented Feb. 26, 1918.

2 SHEETS—SHEET 2.

UNITED STATES PATENT OFFICE.

CLARENCE L. BAIR, OF DETROIT, MICHIGAN, ASSIGNOR TO AUTO SPECIALTIES MANUFACTURING CO., OF ST. JOSEPH, MICHIGAN, A CORPORATION OF CALIFORNIA.

BOW-TOP HOLDER FOR TOPS WITH NON-DETACHABLE REAR CURTAINS.

1,257,782.

Specification of Letters Patent. Patented Feb. 26, 1918.

Application filed June 3, 1916. Serial No. 101,455.

To all whom it may concern:

Be it known that I, CLARENCE L. BAIR, a citizen of the United States, residing at Detroit, in the county of Wayne and State of Michigan, have invented a certain new and useful Improvement in Bow-Top Holders for Tops with Non-Detachable Rear Curtains, of which the following is a specification.

10 This invention relates to bow top holders for vehicles of the general type shown in my Patent Number 1,010,110, issued November 28, 1911, designed to hold the supporting bows of a vehicle top in separated 15 position one from the other when the top is collapsed. The object of this invention is to provide a holder of this class of such a construction that it can be used to confine the bows of a top which has a solid rear 20 curtain attached to the bottom bow of the vehicle, which class of top cannot be taken care of with the bow holders of types shown in my above mentioned patent. The invention consists in providing a bow holder 25 which, while capable of grasping and separating the bows of the top, is open on the side toward the vehicle so that the continuous curtain above referred to is provided for when the top is collapsed without 30 injury thereto; this, in combination with means for moving the holding parts of the bow holder out of the path of travel of the bows, as they move between open and closed 35 position, and vice versa.

35 The invention further consists in the features and details of construction hereafter more fully set forth in the specification and claims.

Referring to the drawings, in which similar numerals indicate the same parts throughout the several views,

Figure 1 is a perspective view of a vehicle and top showing the device of this invention applied thereto in position ready to 45 have the bows of the top lowered into it prior to securing them in place.

Fig. 2 shows the top collapsed and the device of this invention applied to the bows.

Fig. 3 is a side view of the device of this 50 invention in the same position as in Fig. 2, the bows and solid curtain being shown in cross-section.

Fig. 4 is a changed position view of the parts of Fig. 3.

55 Fig. 5 is a perspective view, reduced, of

the device of Fig. 3, removed from the vehicle.

Fig. 6 is a perspective view of a control plunger removed from the other parts of the device.

Fig. 7 is a perspective view of a control plunger removed from the other parts of the device.

The top to be taken care of by the device of this invention is illustrated in the drawings as having side bows 10, 11, 12 and 13 and differs from tops ordinarily taken care of by devices of the type of my prior patent 65 in that the back of the vehicle is closed by a solid curtain 14, which is, as shown in Figs. 1 and 3, attached at its sides to the bottom bow 10, as well as to the vehicle body 16 in the line 18, it being obviously attached to 70 the upper portion or top proper in the line 20, and the general problem solved by this invention is to provide means for readily securing all of these bows 10—13 together while accommodating this curtain 14, permanently attached to the bottom bow 10.

75

The bow holder for accomplishing the desired result comprises a relatively short

fixed base or stock 22 secured to the vehicle

body 16 by any well known securing device,

80 such, for instance, as pin 24, forming no

part of this invention.

The stock 22 is provided with two suitably arranged hinge pivot pins 26 and 28

designed to accommodate, respectively, the 85

two swinging arms 30 and 32, shown in the

drawings. Arm 32 corresponds generally

with the swinging arm of the bow holder

of my said prior patent and is accordingly

provided with separator members 34 adapt-

90 ed to operate between adjacent bows, as

shown. At the upper end of swinging arm

30 is another hinge pivot 36 to which is piv-

otally attached relatively short arm 38 de-

signed to, as shown, swing down over at 95

least the uppermost bow 13 and thus firmly

secure it in position in the manner de-

scribed. The stock 22 and the arm 30 are

lined with a rubber cushion 40. All that is

desired for swing of arm 30 is that it shall 100

swing from the position of Fig. 3 to that of

Fig. 4 in which it is out of the way of the

descending bow tops 10—13 as the vehicle

top is lowered from the position shown in

Fig. 1 to that of Fig. 2, accordingly arm 30 105

is provided with a projecting finger 31

which engages internal wall 33 inside of

stock 22, and this limits the movement of

arm 30 beyond the position of Fig. 4. Simi-

larly and for the same reason, the movement 110

of arm 32 beyond the position of Fig. 4 is not desired, and this is accomplished in two ways; first, by constructing the shape of bearing surface 39 of the pivot joint, details not shown, so as to stop this movement, and, second, and more important, by interconnecting arm 32 with finger 31 of arm 30. To accomplish this said lever 32 is provided with a depending finger or lug 42 entering 10 a hole 44 formed in a plate 46 carried by arm 48 depending from a piston or plunger 50 slideable backward and forward within the tubular opening 52 formed in the stock 22, the finger 31 on arm 30 entering a recess 15 53 in said piston, so that the two arms 30 and 32 necessarily move in unison. The upper end of arm 30 is provided with a convex surface or lug 54 adapted, when the parts are in the position shown in Fig. 3, to lie 20 nicely in a recess 56 formed for the purpose in the back of arm 30. On the back of arm 32 and in the particular case here illustrated on the opposite side thereof from lug 54 is a similar recess 58 in which the point 60 of 25 operating hand lever 62 is correspondingly adapted to rest when the parts are in the position of Fig. 3. Owing to the fact that the pivots 26 and 28 and the interlocked members 54 and 56 form three corners of a triangle, the arms 30 and 32 are necessarily 30 rigidly locked in the position of Fig. 3.

Connecting lever 62 and arm 38 is a spring link 64, made, as shown, in the form of a parallelogram whose ends form the pivotal connections 66 and 68 of the link with the lever and arm. These pivots are so located that when the device is closed the sides of the link 64 are below the pivot 36 with the result that when the parts are in the position shown in Fig. 3 the tension of this link 64 holds both arm 38 and lever 62 in the position shown in Fig. 3. When, however, the operator takes hold of handle 70 on lever 62 and swings it in a counter-clockwise direction about its end 60, all the parts 45 may be moved to the position shown in Fig. 4. It is noticeable that when the parts are in the position of Fig. 4, wherein the bows can swing into the holder, the operator can, by manipulating only lever 62, close the device to the position of Fig. 3.

Obviously, the device shown and described takes care of the fixed curtain 14 in good shape.

55 The application of the locking device 70, 72, 74 at the top of the swinging arm 42 is reserved for and claimed in my prior application, Ser. No. 72,624, filed January 17, 1916.

60 Having thus described my invention, what I claim as new and desire to secure by Letters Patent, is:—

1. In a device of the class described, the combination with a fixed block or stock 65 adapted to be secured to a vehicle body, a

bow retaining arm mounted on said stock, so as to move toward and from the vehicle to which the stock is attached, adapted in said first position to engage vehicle top bows on the outside thereof, a second movable arm 70 mounted at the free end of said first arm adapted to move over a bow lying adjacent to the first mentioned arm and confine it adjacent to said arm, a third arm movably connected to said stock so as to lie outside 75 the first mentioned arm and adjacent thereto, and a locking device coöperating with the second and third arms for securing all of the parts in position to retain the bows of a vehicle within the device, for the purposes 80 set forth.

2. In a device of the class described, the combination with a fixed block or stock adapted to be secured to a vehicle body, a bow retaining arm mounted on said stock, 85 so as to move toward and from the vehicle to which the stock is attached, adapted in said first position to engage vehicle top bows on the outside thereof, a second movable arm mounted at the free end of said first arm adapted to move over a bow lying adjacent to the first mentioned arm and confine it adjacent to said arm, a third arm movably connected to said stock so as to lie 90 outside the first mentioned arm and adjacent thereto, means inter-connecting the first and third arms so that they must move in unison, and a locking device coöperating with the second and third arms adapted, when released, to permit movement of all 95 three arms to a position where they clear the path of travel of the bows of the vehicle top to which the device is applied, and adapted, when locked, to rigidly secure said arms in such a position that the first arm is adjacent to the folded in bows of the top, and the second arm secures at least one bow 100 to the second arm, for the purposes set forth.

3. In a device of the class described, the combination with a fixed block or stock adapted to be secured to a vehicle body, a bow retaining arm mounted on said stock, so as to move toward and from the vehicle to which the stock is attached, adapted in said first position to engage vehicle top bows on the outside thereof, a second movable arm mounted at the free end of said first arm adapted to move over a bow lying adjacent to the first mentioned arm and confine it adjacent to said arm, a third arm movably connected to said stock so as to lie outside 115 the first mentioned arm and adjacent thereto, means inter-connecting the first and third arms so that they must move in unison, 120 means limiting the range of movement of said two arms, and a locking device coöperating with the second and third arms adapted, when released to permit movement of all three arms to a position where they clear 125 130

the path of travel of the bows of the vehicle top to which the device is applied, and adapted, when locked, to rigidly secure said arms in such a position that the first arm is adjacent to the folded in bows of the top and the second arm secures at least one bow to the second arm, for the purposes set forth.

4. In a device of the class described, the combination with a fixed block or stock adapted to be secured to a vehicle body, a bow retaining arm pivoted to said stock, so as to move toward and from the vehicle to which the stock is attached, adapted in said first position to engage vehicle top bows on the outside thereof, a second movable arm pivoted to the free end of said first arm, adapted to swing over a bow lying adjacent to the first mentioned arm and confine it adjacent to said arm, a third arm pivoted to said stock so as to lie outside the first mentioned arm and adjacent thereto, and a locking device coöperating with the second and third arms for securing all of the parts in position to retain the bows of a vehicle within the device, for the purposes set forth.

5. In a device of the class described, the combination with a fixed block or stock adapted to be secured to a vehicle body, a bow retaining arm pivoted to said stock so as to move toward and from the vehicle to which the stock is attached, adapted, in said first position, to engage vehicle top bows on the outside thereof, a second movable arm pivoted to the free end of said first arm adapted to swing over a bow lying adjacent to the first mentioned arm and confine it adjacent to said arm, a third arm pivoted to said stock so as to lie outside the first mentioned arm and adjacent thereto, means inter-connecting the first and third arms so that they must move in unison, and a locking device coöperating with the second and third arms adapted, when released, to permit movement of all three arms to a position where they clear the path of travel of the bows of the vehicle top to which the device is applied, and adapted, when locked, to rigidly secure said arms in such a position that the first arm is adjacent to the folded in bows of the top and the second arm secures at least one bow to the second arm, for the purposes set forth.

6. In a device of the class described, the combination with a fixed block or stock adapted to be secured to a vehicle body, a bow retaining arm pivoted to said stock so as to move toward and from the vehicle to which the stock is attached, adapted, in said first position, to engage vehicle top bows on the outside thereof, a second movable arm pivoted to the free end of said first arm, adapted to swing over a bow lying adjacent to the first mentioned arm and confine it adjacent to said arm, a third arm pivoted to said stock so as to lie outside the first

mentioned arm and adjacent thereto, means inter-connecting the first and third arms so that they must move in unison, means limiting the range of movement of said two arms, and a locking device coöperating with the second and third arms adapted, when released, to permit movement of all three arms to a position where they clear the path of travel of the bows of the vehicle top to which the device is applied, and adapted, when locked, to rigidly secure said arms in such a position that the first arm is adjacent to the folded in bows of the top and the second arm secures at least one bow to the second arm, for the purposes set forth. 80

7. In a device of the class described, the combination with a fixed stock or block adapted to be secured to a vehicle body, a bow retaining arm pivoted at one end to said stock, and movable toward and from the vehicle to which the stock is attached between two different positions; in one of which the bows of the vehicle top can freely move from open to closed position without interference by said arm and attached parts, 85 and in the other of which said arm is adjacent to the folded in bows and outside thereof; a second arm pivoted to the opposite end of said first arm adapted to swing over and embrace a vehicle bow adjacent to that end of the first arm, a third arm lying outside the first arm pivoted at one end to said stock and swinging in the same plane as the first arm, means inter-connecting the first and third arms so that moving either moves 90 the other, interfitting parts on the first and third arms adapted to fit together when the parts are in the position of the first arm, wherein the vehicle top bows are retained in closed position, and a locking device coöperating with the second arm and the third arm adapted to secure the locking of said interfitting parts between the second and third arms, for the purposes set forth. 95

8. In a device of the class described, the combination with a fixed block or stock adapted to be secured to a vehicle body, a bow retaining arm mounted on said stock, so as to move toward and from the vehicle to which the stock is attached, adapted in 110 said first position to engage vehicle top bows on the outside thereof, a second movable arm mounted at the free end of said first arm adapted to move over a bow lying adjacent to the first mentioned arm and confine it adjacent to said arm, a third arm movably connected to said stock so as to lie outside the first mentioned arm and adjacent thereto, a piston or plunger mounted in the stock to slide transversely thereof, projecting fingers inter-connecting the first arm and said piston and the third arm and said piston so that moving either arm necessarily moves the other arm, and a locking device 115 coöperating with the second and third arms 120

125

130

adapted, when released, to permit movement of all three arms to a position where they clear the path of travel of the bows of the vehicle top to which the device is applied 5 and adapted, when locked, to rigidly secure said arms in such a position that the first arm is adjacent to the folded in bows of the top, and the second arm secures at least one bow to the second arm, for the purposes 10 set forth.

9. In a device of the class described, the combination with a fixed stock or block adapted to be secured to a vehicle body, a bow retaining arm pivoted at one end to 15 said stock and movable toward and from the vehicle to which the stock is attached between two different positions; in one of which the bows of the vehicle top can freely move from open to closed position without 20 interference by said arm and attached parts, and in the other of which said arm is adjacent to the folded in bows and outside thereof; a second arm pivoted to the opposite end of said first arm adapted to swing over 25 and embrace a vehicle bow adjacent to that end of the first arm, a third arm lying outside the first arm pivoted at one end to said stock and swinging in the same plane as the first arm, a piston or plunger mounted in 30 the stock to slide transversely thereof, projecting fingers inter-connecting the first arm and said piston and the third arm and said piston so that moving either arm necessarily moves the other arm, interfitting parts on 35 the first and third arms adapted to fit together when the parts are in the position of the first arm, wherein the vehicle top bows are retained in closed position, and a locking device coöperating with the second 40 arm and the third arm adapted to secure the locking of said interfitting parts between the second and third arms, for the purposes set forth.

10. In a device of the class described, in 45 combination with a stock and two arms pivoted thereto so as to swing in a given plane, a piston slidable through an opening in the stock in a direction generally transverse to the lengths of said two arms, members 50 loosely connecting each of said pivoted arms to said piston whereby moving either arm reciprocates the piston and consequently swings the other arm, and means for detachably securing one of said arms in 55 a predetermined fixed position.

11. In a device of the class described, in combination with a stock adapted to be secured to a vehicle body, an arm pivoted to said stock adapted to move toward and from the vehicle body to which the stock is attached between two positions; in one of which it clears the path of travel of vehicle top bows on said vehicle and in the other of which it lies against the outside of said bows; a securing device on the opposite end 60 of said lever movable between two positions, in one of which it embraces and secures a vehicle top bow against said arm, and a device outside of said swinging arm composed of two mechanisms coöperating together, one pivoted to the stock, the other pivoted to the securing device, adapted, when brought together in coöperative position, to force said arm to the position where it lies adjacent to the bows of the vehicle 65 top and to simultaneously fasten said securing device upon the bow adjacent thereto. 70

12. In a device of the class described, in combination with a stock adapted to be secured to a vehicle body, an arm pivoted 80 to said stock adapted to move toward and from the vehicle body to which the stock is attached between two positions; in one of which it clears the path of travel of the vehicle top bows on said vehicle and in the 85 other of which it lies against the outside of said bows; a securing device on the opposite end of said lever movable between two positions; in one of which it embraces and secures a vehicle top bow against said arm, a 90 device outside of said swinging arm composed of two mechanisms coöperating together, one pivoted to the stock, the other pivoted to the securing device adapted, when brought together in coöperative position, to 95 force said arm to the position where it lies adjacent to the bows of the vehicle top and to simultaneously fasten said securing device upon the bow adjacent thereto, and one single lever manipulated by the user to 100 cause said coöperation of said last mentioned mechanisms.

In witness whereof, I have hereunto subscribed my name in the presence of two witnesses.

CLARENCE L. BAIR.
